UNITED STATES PATENT OFFICE.

CLARENCE D. TRUSSELL, OF POUGHKEEPSIE, NEW YORK, ASSIGNOR TO TRUSSELL MANUFACTURING COMPANY, OF POUGHKEEPSIE, NEW YORK, A CORPORATION OF NEW YORK.

LOOSE-LEAF BOOK.

Application filed January 4, 1923. Serial No. 610,607.

To all whom it may concern:

Be it known that I, CLARENCE D. TRUSSELL, a citizen of the United States of America, residing in Poughkeepsie, in the 5 county of Dutchess and State of New York, have invented certain new and useful Improvements in Loose-Leaf Books, of which the following is a specification.

This invention relates to loose-leaf books 10 of the ring binder type, the leaves having marginal perforations engaged by hooks or half-rings which when closed together form closed rings. In such books the hooks or half-rings are commonly carried by plates 15 or other carrying means which are acted on by spring pressure in such manner that when the hooks are closed they are held closed by the spring stress, and when opened they are held open thereby. Commonly a back plate 20 of spring metal is employed, the turned-in edges of which embrace the outer edges of hook plates which at their inner edges engage each other with a rocking joint so as to operate with a toggle action by reason of 25 the inward pressure upon them of the spring plate. It has been common to cover the spring plate with a top plate or cover plate which has turned-in edges embracing within them the flanges of the spring plate. 30 The object of the present invention is to produce a book which shall be so thin as to be carried readily and conveniently in the pocket. The ordinary loose-leaf books of the 35 type above described are considerably thicker at the back portion where the binding devices are located than elsewhere, and the thickness of this back portion is such that many persons who desire a loose-leaf book for carrying in the pocket object to those of 40 the ring type for this reason. As books of the ring type, the leaves of which are readily removable and replaceable individually, are much more convenient and desirable than those of any other type, it is important to 45 overcome the one defect of such books, namely, their undesirable thickness at the metal portion or loose-leaf binding means.

According to the present invention the 50 desirable thinness is obtained by resort to two new features of construction, namely, an improvement in the plate construction whereby the top plate, instead of embracing the flanges of the spring back plate, is itself 55 embraced between those flanges, so that it does not add to the width of the book; and

a reciprocal construction of the metal binding device and covers such that the greater part of the thickness of the rings and a portion of the width of the back-plate are received within the thickness of the covers, so 60 that the book is made thinner to the extent of the overlapping of the thicknesses of these members. The invention also provides other improvements in construction, as will be explained. 65

Referring to the drawings,—

Figure 1 is an elevation of the back portion of a loose-leaf book, its covers being laid open flat, its hooks being open, and the loose leaves removed. 70

Fig. 2 is a transverse section on the line 2—2 in Fig. 1, the hooks being closed.

Fig. 3 is a similar transverse section on the line 3—3 in Fig. 1, the hooks being open. 75

Fig. 4 is a transverse section on the plane 75 of the line 4—4 in Figs. 6 and 7.

Fig. 5 is a transverse section answering to Fig. 3, but showing the book closed.

Fig. 6 is an elevation of the hooks and hook plates removed. 80

Fig. 7 is a related elevation of the top plate removed. 85

Fig. 8 is a longitudinal section on the line 8—8 in Fig. 1, showing the opener and adjacent portions. 85

Fig. 9 is a transverse section on the line 9—9 in Fig. 8.

The invention is shown as applied to a loose-leaf book of generally well known construction, comprising half-rings *a a*, of which three pairs are shown, mounted on or formed integrally with hook plates *b b*, these parts being shown separately in Fig. 6, and assembled within the inturned flanges of a spring back plate *c* of usual construction. 90 The top plate *d*, shown separately in Fig. 7, is of special construction, its side flanges being carried downwardly and outwardly within the flanges of the back plate, as best shown in Fig. 2. 100

The cover *e* is shown as made of one piece of leather or similar material, the sides and back being continuous or integral, the back being clamped directly against the spring plate *c* by an outer binding plate *f* which is 105 formed at its ends or elsewhere with ears *g*, shown in dotted lines in Fig. 3, which pass through the leather, and the ends of which are turned down against the concave side of the spring plate *c*, whereby to permanently 110

unite the two plates. The leather is grooved to make it thinner and more flexible closely adjacent the back plate, whereby to form a sort of integral hinge for the sides. In this respect the hinge construction is the same as set forth in my Patent No. 1,104,394, dated July 21, 1914.

The hook plates *b b* are formed with outward projections *h* which are embraced within the flanges of the back plate *c*, and receive the inward pressure of these flanges. The plates *b b* are also formed with portions *i i* projecting toward each other in suitable locations, preferably coincident with the hooks *a a*, and these portions are constructed to engage each other to form a sort of hinge connection. This construction may consist of a V-edge on the one part, and a groove in the other, to form a modified knife-edge hinge. The operation is that which is well understood in this type of binders, the spring back plate pressing inwardly against the portions *h* and thereby forcing the plates together, and the latter rocking on these knife-edged joints as the hooks open and close. The plates are in alignment at an intermediate point in the movement, and buckle with the toggle action to either side of such position of alignment, so that the spring pressure is utilized to press the hooks together when closed, and hold them apart when opened.

It is usual but not essential in such ring binders to provide a top plate or cover plate which affords a better finish than to leave the hook plates visible. For this purpose the cover plate *d* is applied. This plate in the present construction is made of suitably thin metal, and is carried down between the flanges of the back plate, as shown at *j j*, its side portions being turned outwardly at *k k* to enter within the hooked flanges of the back plate. These out-turned flanges *k* are discontinuous, being notched away at *l l* opposite the outer projections *h h* of the hook plates to afford room for the latter to engage within the hook flanges of the back plate. The top plate is also more deeply notched at *m m* opposite the respective hooks *a a* to afford room for the hooks where they spring from the hook plates. The portions *n* of the top plate between the notches *m* come over the inner projections of the hook plates and serve to arrest their upward movement, thus limiting the opening movement of the hooks as shown in Fig. 3.

The top plate is also by preference formed with end extensions *p p* of such shape that when the parts are assembled in place these may be bent down to thereby close the otherwise open ends of the back plates *c* and form a neat finish.

The width of the metal binding devices is not only reduced by bringing the flanges of the top-plate within (instead of outside

of) the flanges of the back-plate, but the latter flanges are embedded within the thickness of the sides of the cover. This is accomplished by reducing the thickness of the cover adjacent the side flanges of the back-plate *c* as shown at *e e'*, so that when the book is closed, as shown in Fig. 5, these flanges penetrate within the thickness of the sides, thus materially reducing the external thickness of the closed book at the back. 75

When the hooks are closed and the covers are closed together, as shown in Fig. 5, the hooks are received within grooves or slots *q q* in the sides of the cover, as clearly shown in that figure. For the utmost compactness 80 the cover sides may be formed with slots *q q* as shown in Figs. 1 and 3, and at the lower side in Fig. 5. These slotted portions receive the projection of the hooks fully within them, so that the total thickness of 85 the book is reduced to the diameter of the rings formed by the abutting hooks. But for a better external finish the sides of the cover may be formed with grooves as shown at *q' q'* in Fig. 2, and as shown at *q' q'* in the 90 upper part of Fig. 5, these grooves being of a depth somewhat less than the thickness of the leather, so as to leave its outer surface integral, while yet receiving the greater part of the thickness of the hooks within the 95 grooves. By the use of either the slots or the grooves the book may be made with its back or binding portion so thin as to not perceptibly exceed in thickness the remaining portion of the book when it is carrying 100 its full complement of leaves. This is shown in Fig. 5, where the lines *r r* indicate the outer leaves of a full book, the thickness of the leaves being thus slightly less than the inner diameter of the closed rings, and the 105 covers being of a thickness slightly greater than the thickness of the rings, so that the closed book is of very nearly uniform thickness from back to edge.

To facilitate opening such a book it is desirable to have a rocking opener or thumb-piece *s*. This is shown (according to my Patent No. 1,468,846, dated Sept. 25, 1923) as formed of sheet-metal, in a plane coinciding with the medial plane of the binding. 110 mechanism, namely, that indicated by the line 8-8 in Fig. 1, and formed as a lever passing through a slot *t* in the cover plate, with its thumb portion above this plate, and having a rocking contact with the back plate *c*, so that it may be tilted by pressing down the thumb-piece *s*, and having a short arm *u* which engages under either one or both of the hook plates *b b*, so that when the thumb-piece is pressed down the upward movement of the arm *u* pushes up the meeting portions of the hook plates and opens the hooks. For better guiding this opener laterally the hook plates may be formed with 115 prolonged ends or fingers *v v*, Figs. 6 and 9, 120 125 130

which extend along opposite sides of the 5 opener. The escape of the opener when not in use is prevented by a projecting toe *w* which strikes against the under side of the top plate. When the top plate, with the 10 hooks and hook plates, are slid longitudinally out of the back plate far enough to release the opener from contact with the latter, the opener may be removed by tipping 15 it up to the position shown in dotted lines in Fig. 8. In this position a notch *s'* in the 20 opener is carried into engagement with the end of the slot *t*, whereby the projection *w* is brought within the length of the slot, so that the opener may be lifted out. This construction is mainly useful in the reverse 25 operation of assembling the parts. The opener is guided laterally by the sides of the slot *t*, and by the inner faces of the fingers *v v*, as shown in Fig. 9, whereby it is kept from 30 tilting sidewise.

While the described construction is the preferred embodiment of the invention, yet it is to be understood that it may be varied 25 in matters of detail within the scope of the appended claims.

I claim as my invention:

1. A loose-leaf book comprising a spring 30 back plate, hooks, and hook carriers, the latter embraced between the flanges of the back plate with a rocking movement, and a cover plate having its marginal portions engaged between the edges of the back plate.

2. A loose-leaf book according to claim 1, 35 the hook carriers having outward projections engaged by the back plate, and the cover plate cut away coincidently with said projections.

3. A loose-leaf book according to claim 1, 40 the cover plate having down-turned sides entering within the hooked edges of the back plate and having out-turned edges engaging under the edges of the back plate.

4. A loose-leaf book according to claim 1, 45 the hook carriers formed with inward pro-

jections having a rocking engagement, and the cover plate overlying such projections and adapted to arrest the upward movement thereof and thereby limit the opening movement of the hooks.

5. A loose-leaf book according to claim 1, comprising spring-actuated hooks and a cover which is partially cut away opposite the hooks, so that the latter enter within the thickness of the cover and reduce the thickness of the book. 50

6. A loose-leaf book comprising hooks and hook plates, a spring back plate, a cover plate having a slot, and an opener, the latter formed as a plate passing through said slot 60 and normally confined in place thereby, having an arm engaging beneath the hook plates, and a toe projecting beneath the top plate, and having rocking contact with the back plate, said opener having also a notch 65 adapted when tilted beyond its normal movement to receive the top plate beyond the end of said slot to permit the insertion of the opener.

7. A loose-leaf book comprising hooks and 70 hook plates, a spring back plate, a cover plate, and an opener, the latter formed as a plate passing through a slot in the cover plate, having an arm engaging beneath the hook plates, and the latter having fingers 75 embracing the sides of the opener, whereby it is guided laterally.

8. A ring book or binder comprising binding elements and a cover, the binding elements consisting of hooks with spring- 80 pressed carriers therefor and a back-plate, the cover being longitudinally grooved to receive the side edges of the back-plate, whereby the width of the binding elements lies partly within the thicknesses of the sides of 85 the cover when the book is closed.

In witness whereof I have hereunto signed my name.

CLARENCE D. TRUSSELL.
